ROLLER SKATE

Woodrow T. Engman, 13210 N. 26th Place,
Phoenix, Ariz. 85032

Filed Feb. 26, 1973; Ser. No. 335,691

Term of patent 14 years

Int. Cl. D21—01

U.S. Cl. D34—14 C

Fig. 1

Fig. 2

Fig. 3

FIG. 1 is a perspective view of a roller skate showing my new design;

FIG. 2 is a right side elevational view; and,

FIG. 3 is a bottom plan view.

For convenience of illustration the straps and buckles shown in FIG. 1 have been omitted from FIGS. 2 and 3.

I claim:

The ornamental design for a roller skate, as shown and described.
